UNITED STATES PATENT OFFICE.

JOSEPH M. BECKER AND ALEXANDRE SAGGESE, OF NEW YORK, N. Y.

BOOK-PROTECTOR.

SPECIFICATION forming part of Letters Patent No. 446,052, dated February 10, 1891.

Application filed August 6, 1890. Serial No. 361,159. (No model.)

To all whom it may concern:

Be it known that we, JOSEPH M. BECKER and ALEXANDRE SAGGESE, citizens of the United States, and residents of New York, in 5 the county of New York and State of New York, have invented certain new and useful Improvements in Book-Protectors, of which the following is a specification.

Our invention relates to improvements in 10 book-protectors; and the invention consists of a book-protector made of paper, canvas, leather, or any other suitable material, having flaps provided with eyelets, through which eyelets laces or cords are drawn, by means of 15 which the protector can be easily and quickly applied to the covers of a book, pamphlet, or magazine.

In the accompanying drawings, Figure 1 represents an open book with our improved 20 book-protector applied to the covers of the same, and Fig. 2 is a blank of the book-protector.

Similar letters of reference indicate corresponding parts.

25 A in the drawings represents a blank of paper, canvas, leather, or any other suitable material, having two incisions *a a* opposite each other and four incisions *b b b b* at its outer ends. By these incisions four flaps *d d* 30 and two flaps *e e* are formed, the flaps *d* being located between the incisions *a* and *b* and the flaps *e* between the incisions *b b*, as clearly shown in Fig. 2. It is not necessary that these incisions must have the forms 35 shown in the drawings. Any incisions in the places indicated by the reference-letters *a* and *b* will have the same result, as thereby the flaps *d* and *e* are formed, which are not dispensable with my improved book-protector. 40 The flaps *d* and *e* are provided with eyelets *f*, through which a ribbon, tape, or cord *g* is drawn, as clearly shown in the drawings.

Our book-protector is applied to the covers 45 of a book, pamphlet, or magazine in the following way: The opened book *B* is placed on

the blank of the protector, so that the back of the book is in a line between the incisions *a a*. The flaps *d d* and *e* at one side of the back of the book are then bent over the inside of the cover *B'* and the ribbon or tape in 50 the eyelets drawn tight and the ends of the same knotted together, as shown in Fig. 1. To the other cover of the back the flaps *d d* and *e* are applied in the same manner. The protector thus applied to a book or magazine 55 cannot get loose and can only be removed by unknotting the ribbon or tape.

Instead of ribbons or tapes, elastic rubber bands may be drawn through the eyelets, so that by the bent-over flaps pockets are formed, 60 into which the covers of the book are pushed.

It is evident that our book-protector can also be used as a portfolio, as the pockets which are formed by the flaps *d* and *e* may serve as receptacles for documents and other papers. 65

Our book-protectors are manufactured in various sizes, according to the sizes of the books. They are especially adapted for school-books, account-books, and magazines.

We are aware that book-protectors having 70 flaps which inclose the book-covers are old and well known, and therefore we do not claim such book-protectors, broadly.

What we claim as our invention is—

A book-protector consisting of a blank of 75 canvas, paper, or other suitable material having flaps *d d* and *e*, said flaps being provided with eyelets and adapted to be bent over to inclose a book-cover, in combination with ribbons or tapes passing through said eyelets and 80 knotted together at their ends, substantially as set forth.

Signed at New York, in the county of New York and State of New York, this 2d day of August, A. D. 1890.

JOSEPH M. BECKER.
ALEXANDRE SAGGESE.
